UNITED STATES PATENT OFFICE

WALTER F. KAUFMAN, OF LANCASTER, PENNSYLVANIA, ASSIGNOR TO ARMSTRONG CORK COMPANY, OF PITTSBURGH, PENNSYLVANIA, A CORPORATION OF PENNSYLVANIA

COLOR FOUNTAIN FOR BLOCK PRINTING MACHINES

Application filed August 16, 1928. Serial No. 299,969.

This invention relates to the art of printing, and is for a color carriage of the type commonly used in block printing machines, such, for instance, as those used in the decoration of linoleum and felt base floor coverings.

In block printing machines the printing blocks are arranged transversely of the direction of travel of the strip of material being decorated. The blocks are moved down into contact with the material to be printed and then lifted, and while they are elevated a paint fountain moves across the surface thereof to apply color to the printing surface thereof. It has been proposed to divide the paint fountain longitudinally into a plurality of compartments whereby different portions of the roll in the fountain will apply different colored paint to different divisions of the printing block.

The partitions in the color box must be of appreciable width in order to prevent the color from one compartment working over into the color in the next compartment. By reason of this the portions of the block located over the partitions do not receive color at all. This necessitates specially adapting the pattern of the rug to the divisions in the paint carriages so that the portions of the pattern which must be left blank by one block are filled in by a succeeding block, the partitions of the carriages for successive blocks being staggered.

With the present arrangement there is provided a color box so divided that the color divisions will meet on the same line and no space needs to be left by reason of the partitions in the trough. The invention can be adapted to use in machines wherein the ordinary printing blocks are employed, or it can be used with machines having the printing blocks divided into a plurality of sections transversely and/or longitudinally as suggested for instance in the application of William Penn Brinton, Serial No. 247,319, filed January 17, 1928. The invention is also adapted for use in an arrangement where vertical movement is effected between the color carriage and the block during the passage of the color carriage under the block, as

disclosed in the application of Robert A. Balderson, Serial No. 291,818 filed July 11th, 1928.

The invention may be readily understood by reference to the accompanying drawings wherein

Figure 1 is a plan view of a color carriage constructed in accordance with my invention, the outline of the printing block being shown in broken lines; and

Figure 2 is a similar view of a slightly modified color fountain.

In the drawings 2 designates a color carriage having a central partition 3 extending longitudinally thereof and dividing the carriage into two compartments 4 and 5. In the compartment 4 are transverse partitions 6 by means of which the compartment 4 is divided into short sections, 4^a, 4^b, 4^c, and 4^d. Similarly the compartment 5 is divided by partitions 7 into relatively short sections 5^a, 5^b, 5^c, and 5^d. The partitions 7 are staggered with reference to the partitions 6. In the particular embodiment shown, the compartment 5^a is longer than the compartment 4^a, while the compartment 4^b is longer than the compartment 5^b, etc.

In the compartment 4^b and in the compartment 4^d are rollers 8^b and 8^d respectively. The rollers 8^b and 8^d are preferably carried on a common shaft 8 which extends throughout the length of the compartment 4 and projects beyond the end thereof, the projecting ends being provided with driving gears as is common in the art. The shaft 8 is packed where it passes through the partitions, as is also known in the art.

In the compartments 5^a and 5^c are color applying rollers 9^a and 9^c respectively, these rollers being carried on the shaft 9 which is arranged similarly to the shaft 8. The right hand end of the roller 9^a and the left hand end of the roller 8^b both extend to substantially the same line X—X. Similarly the right hand end of the rollers 8^b and the left hand of the roller 9^c end on the line Y—Y. The ends of the rollers 9^a and 8^d end on the line Z—Z.

It will thus be seen that no matter how long the compartments 4^a, etc., and 5^a, etc.,

are, the color applying rollers can extend to the same line. When the color carriage passes under the printing block A, roller 9^a will apply color to the section *a* of the block; roller 8^b will apply color to the section *b* of the block; roller 9^c will apply color to the area *c* of the block, and the roller 8^d will apply color to the area *d* of the block. It will be seen that there is no space which is left uncovered between the areas *a*, *b*, *c* and *d*, it being possible to apply the color up to the line of juncture. It is not necessary that a space equal to the width of the partitions 6 or 7 exist, as is necessary with the present practice, where the color carriage contains but a single trough.

The construction shown in Figure 2 is substantially the same as that shown in Figure 1, and the same reference numerals have been used with a prime affixed thereto to designate the corresponding parts. In this arrangement, however, all of the divisions in the compartments 4 and 5 have a color roller. This arrangement can be used in the same way that the arrangement shown in Figure 1 is used by merely leaving some of the compartments empty so that the rolls do not apply paint. This arrangement can also be used with a divided printing block such as shown in the Brinton application or can be used where vertical movement is effected between the block and the carriage during the passage of the carriage under the block as disclosed in the said Balderson application.

While I have shown a particular construction and arrangement of partitions, it will be understood that the invention is not restricted to the particular construction and arrangement of partitions shown and may be otherwise embodied within the scope of the following claims.

I claim:

1. A color carriage having a plurality of longitudinally extending troughs, each of said troughs having transverse partitions therein.

2. A color carriage having a plurality of longitudinally extending troughs divided transversely into compartments, the partitions between the compartments being staggered.

3. A color carriage having at least two longitudinally extending compartments with transverse partitions therein, the partitions in the compartments being staggered, and paint applying rollers in some of the compartments.

4. A color carriage having two series of paint holding compartments, one arranged in advance of the other, the ends of the compartments of one series being staggered with respect to the ends of the compartments of the other series, and paint rollers in the compartments, the ends of the rollers in one series of compartments terminating in sub-

stantially the same plane as the opposite ends of the rollers in the other series of compartments.

5. A color carriage having two series of parallel compartments, the compartments of one series overlapping the compartments of the other, and paint applying rollers in some at least of the compartments of each series, the rollers in the compartments of the two series terminating in substantially the same transverse plane. 75

6. The combination with a printing block, of a color carriage for applying different colors to closely adjacent areas of the block, said carriage having two longitudinally extending compartments, a color applying roll in each compartment, the rolls being of less length than the compartments, the right hand end of one roll being in substantially the same plane as the left hand end of the other roll. 80

7. A color carriage having a pair of longitudinally extending compartments, color applying roll sections in each compartment staggered with reference to each other, some of the roll sections in one compartment terminating in substantially the same transverse plane as the opposite ends of the roll sections in the other compartment. 90

8. A color carriage having a pair of longitudinally extending compartments, color applying roll sections in each compartment staggered with reference to each other, some of the roll sections in one compartment terminating in substantially the same transverse plane as the opposite ends of the roll sections in the other compartment, and transverse partitions at the ends of the said roll sections. 95

9. The combination with a printing block of a block printing machine, of a longitudinally divided color box having parallel troughs, a roll section in one trough, a roll section in the other trough, the left hand end of one roll section being in substantially the same plane as the right hand end of the other roll section. 105

10. A color carriage for use in a block printing machine comprising a trough-like body having a single partition extending down the middle thereof, which partition divides the body into two longitudinally extending troughs, and transverse partitions in said troughs, the transverse partitions being in staggered arrangement, and paint-applying rollers lying in compartments of said troughs formed by the transverse partitions. 115

In testimony whereof I have hereunto set my hand.

WALTER F. KAUFMAN.
